UNITED STATES PATENT OFFICE.

WILLIAM HOCHHAUSEN, OF BROOKLYN, NEW YORK.

ELECTRIC SWITCH AND CUT-OUT.

SPECIFICATION forming part of Letters Patent No. 447,826, dated March 10, 1891.

Application filed March 12, 1889. Serial No. 303,012. (No model.)

To all whom it may concern:

Be it known that I, WILLIAM HOCHHAUSEN, a citizen of the United States, and a resident of Brooklyn, in the county of Kings and State of New York, have invented a certain new and useful Electric Switch and Cut-Out, of which the following is a specification.

My invention relates to electric switches designed to control the flow of current to an electric translating device—such, for instance, as an electric lamp.

The object of my invention is to provide a simple and effective apparatus in which capacity for the manual and automatic operation of the switch will be combined, thus doing away with two sets of apparatus for securing the two results of an automatic protection of the apparatus from injury and of a manual control permitting the current to be turned onto or off from the lamps at will.

The object of my invention is also to provide a manual and automatic switch apparatus suitable for attachment to ceilings or to other indoor apparatus.

My invention consists, among other things, in the combination, with the switch, of a catch and controlling-magnet which releases the switch, a releasing-button projecting from the case and also adapted to act on the catch, and a resetting arm or lever, also outside the case but connected with the switch for resetting the same, as will be hereinafter described.

My invention likewise consists in certain improved combinations and details of construction to be hereinafter more particularly described, and then specified in the claims.

In the accompanying drawings, Figure 1 is a plan of an apparatus embodying my invention, the cover being removed and the switch shown in position engaged by the catch. Fig. 2 is a plan showing the other position of the switch. Fig. 3 is an elevation and partial section of an apparatus. Figs. 4 and 5 are perspective views of parts of the mechanism. Fig. 6 is a diagram of electrical connections.

A is the base plate or board supporting the switch and adapted to be secured to the ceiling or other convenient support. To said board are attached metal plates B B, having each a clamp-block b, formed in one piece with it and sunk in the material of the board, as shown more clearly in Fig. 3. In these

blocks are formed openings or sockets, as shown, which are in line with openings D D, entering the board from its edge and adapted to receive the supply-wires, whose ends are received in the blocks b and are fastened in place by set-screws C C in the upper surface of the plates B B. From the plates B rise arms F, preferably cast in one piece with the plates and having at their extremities suitable clamping-screws or other devices by which wires entering through a central opening in the cover-plate E may be fastened, thus affording a means whereby an electric lamp or other device may be connected to the supply-wires.

At the opening is a suitable bushing or short section of tubing G, to which may be fastened a pipe or tube, through which the wires fastened to F may be led. The tube or bushing G, which may also serve for the attachment of the base-block for an incandescent lamp, is secured to or cast in one piece with the arch or cross piece H of iron, springing at one end from the base-board and at the other from a horizontally-disposed iron angle-piece I, extending along the side and across one end of the electro-magnet K, which controls the cut-out switch in the manner to be presently described. The piece I is fastened to and in magnetic connection with one end of the core of electro-magnet K, so that the magnetism may be carried around to the armature L, moving in front of the other pole and pivoted in the end of the angle-piece. The object of this arrangement is to increase the magnetic pull upon the armature. The arch or cross piece H and angle-piece I are preferably cast in one piece.

Formed upon or connected with the plates B B are the switch contacts or surfaces m m, which may be connected by a switch-lever M, pivoted in a plate N, secured to the board. A spring O, secured to the under side of the lever M, slides upon the contacts m m with its free ends to make electrical contact therewith. When the lever is in position to connect the contacts m m, it is obvious that the lamp or other device connected with the arms F, and also the magnet K in circuit between plates B B, will be shunted. A spring P tends to throw the switch into position to cut out or shunt the lamp or other device.

R is a catch adapted to engage with the switch-lever and hold it out of action, or in the position indicated in Fig. 1. The catch R is connected to the armature-lever of the 5 electro-magnet and is moved by the magnet so as to release the lever whenever the magnet acquires sufficient power to overcome spring d, tending to hold the armature back or in position to keep the switch-lever locked 10 or by the catch. The switch may also be released at pleasure by a button S, which projects beyond the casing and is secured to a stem carrying a button or cam e, that will engage with the catch R and move the same so 15 as to release the switch-lever when said button is operated. The spindle carrying the cam is guided in an extension i from angle-piece I, and a spring between the button and the said extension tends to hold the lower end of the 20 spindle out of the way of the catch.

The switch-lever may be locked at will by the catch by means of a resetting button, lever, or arm T outside the casing, and connected inside the casing with the switch-lever. 25 For this purpose the arm R projects from a rock shaft or spindle R², mounted on the cross-bar H and carrying within the case an arm R³, connected by a pin with a block of insulating material a² upon the switch-lever. 30 The insulation at a² insulates the lever M from the setting-arm T. Suitable stops limit the play of the parts.

W W are lubricating-buttons designed to hold some lubricating material, such as oil, 35 and placed in position to be rubbed by the contact-spring, so that by each movement the spring shall receive fresh lubrication. These buttons may be blocks or pieces of wood or other absorbent or fibrous material adapted 40 to retain or hold the oil or lubricant. The purpose of lubricating the spring is substantially the same as in the case of commutators for dynamo machines and motors—to wit, to prevent grinding of the metal surfaces and 45 to lessen the oxidization from the action of the atmosphere or the electric spark.

The electro-magnet K is wound with fine wire, so as to be of high resistance, and its terminals are secured to the plates B B by 50 binding-screws or other devices. When so connected, it is obvious that the magnet will be in derived circuit to any device connected to the arms F F. The resistance of the magnet is such that comparatively little current 55 will pass through it.

When an incandescent lamp or other translating device is in electric connection with the supply-wires, by attachment of conductors leading through bushing or opening G 60 to the arms F F the circuits will be as represented in Fig. 6, and the operation of the apparatus will be as follows: To throw current into the lamp or other device V, the setting arm or lever is operated by a stick or 65 by grasping by the hand where it can be readily reached, so as to throw the switch into position where it will be engaged and

held by catch R. In the form of switch here shown the current is caused to flow in the lamp because the shunt formed between contacts m m by the switch is broken; but it will be obvious that other arrangements of contacts and connections might be used for securing the same result. Should the lamp break or its resistance become abnormally high, the magnet will release the switch and the latter will be thrown by its spring and remove the current from the lamp by shunting it. After the lamp is restored, or after normal conditions again exist, the switch may be reset and current turned onto the lamp by the resetting-arm or lever projecting from the cover or casing. The current may be turned off from the lamp at any time at pleasure by simply operating the releasing-button S, which acts upon the catch R in the same manner as the magnet and permits the spring P to throw the switch-lever.

I do not limit myself to switches wherein the arrangement of circuits and contacts is such that the circuit is removed from the lamp by providing a short-circuit path around it, as other arrangements well known in the art might be employed for cutting out the lamp or cutting off the flow of current therefrom without departing from the invention.

What I claim as my invention is—

1. The combination, with a spring-actuated switch, of a catch and a releasing-magnet, all inclosed in a suitable case, a releasing-button having a cam adapted to engage with the edge of the catch, and a resetting arm or lever connected with the switch, as and for the purpose described.

2. The combination, with the base board or support A, of a switch-lever mounted on a vertical spindle on said support and adapted to swing in a plane parallel to the surface of the board, the plates B B, of conducting material, resting on the upper surface of said board and having projecting clamp-blocks sunk beneath the surface of the board and provided with sockets in line with openings extending inward from the edge of the board, and suitable clamp-screws, as and for the purpose described.

3. The combination, with the conducting-plates B B, mounted on the switch board or support A and having clamping-screws for securing the supply-wires, of arms F F, cast in one piece with said plates and extending into proximity to an opening in the cover for the switch, and clamping devices on said arms for connection of the wires leading to the lamp, as and for the purpose described.

4. The combination, with the switch, of a lubricating-button located in position to be rubbed by the contact-surfaces of the switch, as and for the purpose described.

5. The combination, with the switch-lever mounted on a suitable board and having an inclosed cover or case, of an electro-magnet supported by said board and in a branch around the switch, a spring acting on said

lever, a catch carried by the armature of the magnet and engaging with the lever, a button projecting from the case and carrying a cam which may engage with and move the catch, 5 and an arm or lever projecting from the case and connected with said switch-lever, whereby the same may be moved or set in position to be engaged by the catch.

6. The combination, with the electro-magnet mounted in the base-plate with its core parallel to the plane of the plate, of the iron angle-piece for the magnet, the cross-piece or bridge formed in one piece with the angle-piece and rising from the base-plate, and a 15 tube or bushing in said bridge forming a passage for the wires leading to a translating device.

7. The combination, with the base-plate, of the contact carrying-plate B B, fastened to the 20 surface thereof, block b b, let into the base and having sockets adapted to receive the two circuit-wires, arms F F, rising from the plates and having clamps for attachment of the lamp-wires, a switch-lever having contacts 25 adapted to complete the circuit between the plates B B, an electro-magnet having an armature which carries a catch for said lever, a releasing-button adapted to engage the armature-lever, and a resetting-lever engaging 30 with the switch-lever and mounted on a frame rising from the base, as and for the purpose described.

8. The combination, in an electric switch, of a suitable base plate or board A, metal 35 plates B B, secured thereto and having clamp-blocks for attachment of contact-wires, contacts m m, connected with said plates, a lever M, pivoted on the base-plate and carrying a spring O, whose ends slide upon said contacts 40 when the lever turns in a plane parallel to the face of the base, a cross-bar or yoke H, mounted on the base-plate and carrying a rock shaft or spindle provided at its outer end with a resetting arm or handle and at its 45 inner end with an arm connected to the switch-lever M, a catch-lever, also mounted

on the base-plate and adapted to turn in a plane parallel with the base thereof, an armature connected to said lever, an electro-magnet mounted on the base-plate, and a releasing-button for actuating said catch to release 50 the switch, as and for the purpose described.

9. The combination, substantially as described, of a suitable base-plate of insulating material, a switch-lever and a catch, both 55 mounted on said plate and adapted to turn in a plane parallel with the face thereof, an electro-magnet carried by said base-plate and having an iron angle piece or connection I, parallel with the base-plate and connected at 60 its free ends with an armature connected to the catch, an arch or cross piece of iron rising from said angle-piece in a direction at right angles from the base-plate, and a resetting arm or lever secured to a rock shaft or 65 spindle which is mounted in a cross-bar or arch-piece and is connected beneath the same with the switch-lever.

10. The combination, substantially as described, of a base-plate, metal blocks or plates 70 B B, carrying clamp-blocks b and having contacts m, whose contact-faces are parallel with the plane of the base-plate, a switch-lever M, carrying on its under side a spring O, which slides over the contacts m m, the catch-lever, 75 also mounted on the base-plate, an electro-magnet whose armature connects with said catch, a resetting arm or lever mounted on the rock shaft or spindle vertical to the plate and connected with the switch-lever, and a 80 releasing button or spindle mounted on a suitable guide and working at right angles to the base-plate, as and for the purpose described.

Signed at New York, in the county of New 85 York and State of New York, this 21st day of January, A. D. 1889.
